US00D988672S

(12) United States Design Patent (10) Patent No.: US D988,672 S
Han (45) Date of Patent: * Jun. 13, 2023

(54) SHOE

(71) Applicant: NIKE, Inc., Beaverton, OR (US)

(72) Inventor: Charles S. Han, Portland, OR (US)

(73) Assignee: NIKE, Inc., Beaverton, OR (US)

() Term: 15 Years

(21) Appl. No.: 29/850,730

(22) Filed: Aug. 23, 2022

(51) LOC (14) Cl. 02-04

(52) U.S. Cl. USPC D2/947

(58) Field of Classification Search

USPC D2/896, 900, 902, 904, 906–908, D2/916–924, 925–945, 946–962, 969–979

(57)

CLAIM

The ornamental design for a shoe, as shown and described.

DESCRIPTION

FIG. 1 is a side view of a shoe showing my new design; FIG. 2 is a front perspective view thereof; and, FIG. 3 is a rear perspective view thereof. The broken lines and unshaded areas depicting the remainder of the shoe form no part of the claimed design.

1 Claim, 3 Drawing Sheets
